UNITED STATES PATENT OFFICE.

BURT RAMSAY, OF ATTLEBOROUGH, MASSACHUSETTS.

INK-BOTTLE ATTACHMENT.

SPECIFICATION forming part of Letters Patent No. 508,340, dated November 7, 1893.

Application filed July 18, 1893. Serial No. 430,369. (No model.)

To all whom it may concern:

Be it known that I, BURT RAMSAY, of Attleborough Falls, in the State of Massachusetts, have invented certain new and useful 5 Improvements in Ink-Bottle Attachments; and I do hereby declare that the following is a full, clear, and exact description of the invention, which will enable others skilled in the art to which it appertains to make and use 10 the same, reference being had to the accompanying drawings, and to the letters of reference marked thereon, which form part of this specification.

This invention relates to certain improvements in ink well or bottle attachments.

The object of the invention is to provide an improved attachment for ink wells or bottles, exceedingly cheap, simple and durable in construction, composed of a minimum number 20 of parts and which can be applied to any ordinary ink bottle and which will normally seal the mouth or opening into the ink bottle so as to effectually prevent evaporation of the ink and which will easily open on the insertion 25 of a pen to permit the pen to enter the bottle.

The invention consists in certain novel features of construction and in combinations of parts more fully described hereinafter and 30 particularly pointed out in the claims.

Referring to the accompanying drawings, Figure 1, is a sectional view showing a bottle provided with my improvement. Fig. 2, is a sectional view (partially in elevation) through 35 a bottle provided with my attachment, showing a pen depressing the parts to receive ink. Fig. 3, is a top plan view of a bottle having the attachment. Fig. 4, is a detail elevation of the attachment, the valve being detached, 40 and showing the spring before being reversed and inserted in the bottle neck. Fig. 5, shows, in perspective, the attachment in the position it assumes when in the bottle and depressed by the pen.

45 In the drawings the reference letter *a* indicates any ordinary ink bottle provided with the mouth or opening *b*, as usual.

The particular object of this invention is to provide improved means for maintaining the 50 mouth or neck of an ink bottle sealed or closed so that there will be no evaporation of the ink,

and so that dust or dirt will not enter the ink, and which will permit insertion of a pen or other article into the ink at any time without in any way injuring the fine point of the pen, 55 and without causing any annoyance or extra labor or operation on the part of the writer or the person using the instrument inserted in the ink.

The present attachment or device consists 60 of a volute spring *c*, suspended in the mouth or neck of the bottle by having its upper convolution or ring *d* resting on the top or upper flange of the mouth of the bottle so that the spring has a constant tendency to draw up- 65 wardly and hold the valve *e* attached to its lower end against and closing the lower end of the mouth of the bottle. This valve *e*, is preferably composed of a flexible disk, circular if desired, and formed of any suitable 70 substance and which will resist the action of the ink and will form an air tight joint around the lower end of the mouth of the bottle so as to prevent access of air to the ink. This spring *c* is formed on a suitable tool or former 75 so as to taper from the large end or convolution *d* that is adapted to rest on the top of the mouth of the bottle, to the small end or convolution which receives and supports the tapered or cup shaped pen guide or guard *h* 80 having a central opening and downwardly projecting neck *i* around which the small end of the spring fits, and to which it is secured in any suitable manner, as by turning over a portion of said neck onto the spring or by 85 any other means or method desired or found suitable to perform the function of securing the cup to the spring. The guide *h*, is so secured and located as to be in the center, approximately, of the neck of the bottle, and 90 so that its central opening through which the pen projects will be approximately over the center of the disk *e*. The end of the wire forming the small end of the coil is projected downwardly, see *f*, from the small end of the 95 coil to one side of the longitudinal center of the coil, so as not to interfere in any way with the projection of the pen through the guide *h*. This end *f* forms or constitutes the connection or securing means between the valve, 100 and the spring and pen guide. This arm *f* being placed to one side of the center or ec-

centrically leaves a clear open space above the valve *e* for the pen to enter the ink. The arm *f* at its lower end has a lateral bend *g*, which permits securing the arm *f* to the center of the valve by passing the lower end of said arm through the valve and upsetting the lower extremity thereof or forming an eye on the same, and it also forms a shoulder on the upper surface of the central portion of the valve which enables the arm to press the valve down. However I do not wish to limit myself to any peculiar manner or means of securing the arm *f* to the valve *g*, and merely specifically describe and show the present mode as a practical and easy method of securing the valve to the spring.

In manufacturing the article the spring is formed as shown in Fig. 4, and the guide *h*, is then suitably secured to the small end of the spring, and then the arm *f*, is secured to the valve *e*, so that the spring is coiled or compressed between the guide *h* and the valve *e* with the large end resting on the valve *e*. Now when it is desired to insert the device in an ink bottle the large end of the spring is drawn upwardly so as to surround the pen guide, and then the valve or disk *e* is bent or doubled so that it can be inserted through the neck of the bottle and will resume its natural normal position against the under side of the neck on the top of the bottle with the large end of the spring resting on the top or mouth of the bottle and the spring coiled around the interior of the neck in a reversed position surrounding the pen guide and drawing the said guide and the valve upwardly so that the valve forms an air tight joint on the lower end of the neck of the bottle. The normal positions of the parts are shown in Fig. 1 with the spring suspended from the mouth of the bottle. When it is desired to dip the pen into the ink the writer merely inserts the pen in the pen guide and the downward pressure which is not more than is ordinarily exerted in inserting a pen into an ink well carries the pen guide and the valve down so that the pen enters the ink, as for instance as shown in Fig. 2 wherein the ink in the bottle is low and the pen moves the valve and cup to the bottom of the bottle showing that all the ink in the bottle can be utilized and the downward movement of the present device is not limited. When the pen is withdrawn the parts assume their normal positions sealing the mouth of the bottle.

It should be observed that the present device is very simple in construction, and composed of a minimum number of parts, but three parts being employed, viz: the pen guide, the spring and the valve. It should also be observed that this device can be used with any ordinary ink bottle, and that it is ready for use at any time, and yet effectually seals the bottle at all times except when the pen is inserted in the ink; also that the pen guide guides the pen into the ink and yet

prevents any injury to the points of the pen as the shoulders of the pens strike against the pen guide and prevent the pen points striking the spring or other part of the device, or the valve.

It is evident that various changes might be made in the forms, constructions and arrangements of the parts described without departing from the spirit and scope of my invention. Hence I do not wish to be limited to the exact construction herein set forth but consider myself entitled to all such changes as fall within the spirit and scope of my invention.

Having thus fully described my invention, what I claim as new, and desire to secure by Letters Patent of the United States, is—

1. The attachment for ink bottles which consists in the combination of the spring, substantially as described, the valve carried thereby, and the pen guide carried by the spring and arranged to move the valve, substantially as described.

2. The ink bottle attachment comprising the volute spring having a valve, and a pen guide attached to one end of the spring, substantially as set forth.

3. The bottle attachment composed of the volute spring having one end arranged to rest on the top or mouth of the bottle, and a disk valve attached to the other end of the spring, as and for the purposes set forth.

4. The herein described article for the purpose described composed of a spring having one end formed to rest on the top or mouth of the bottle, and a disk valve secured to the opposite end of the spring whereby in use the spring is located in the neck of a bottle and holds the valve yieldingly to close the bottom of the neck as and for the purposes set forth.

5. The herein described article consisting of the convolute spring having its large upper end arranged to rest on the top of the neck of the bottle, the tapered pen guide secured to the small end thereof, and the disk valve secured to the spring a distance below the pen guide as and for the purposes set forth.

6. The article for the purpose described consisting of the convolute spring having the large ring at one end to rest on the mouth of the bottle, the valve controlled by said spring, and the cup shaped pen guide having the small end of the spring secured around the central opening of the guide as and for the purposes set forth.

7. The article for the purpose set forth consisting of the convolute spring having an arm extending downwardly from the small end thereof to one side of the longitudinal center of the spring, and the valve, in the shape of a disk, secured to said arm and controlled by the spring as and for the purposes described.

8. The herein described article composed of the reversible volute spring, the pen guide secured to the small end thereof as set forth,

the end of the spring extending downwardly from the pen guide at one side of the longitudinal center of the spring, and having the offset at the lower end, and the disk valve secured to the extremity of said end with said offset bearing on the upper face of the valve, as set forth.

In testimony that I claim the foregoing as my own I affix my signature in presence of two witnesses.

BURT RAMSAY.
